UNITED STATES PATENT OFFICE.

SAMUEL BROOK, OF NEW BEDFORD, MASSACHUSETTS.

DESIGN FOR A KNIFE-SHARPENER.

59,951.

Specification for Design.

Patented Dec. 13, 1921.

Application filed January 10, 1921. Serial No. 436,374. Term of patent 3½ years.

To all whom it may concern:

Be it known that I, SAMUEL BROOK, a citizen of the United States, residing at New Bedford, in the county of Bristol and State of Massachusetts, have invented a new, original, and ornamental Design for a Knife-Sharpener, of which the following is a specification, reference being had to the accompanying drawing, forming part thereof, and in which—

Figure 1 is a side elevation, and Fig. 2 is a plan view of a knife sharpener showing my new design.

I claim:

The ornamental design for a knife sharpener, as shown.

SAMUEL BROOK.
